UNITED STATES PATENT OFFICE.

JOHN DUCHARME, OF ROSETON, NEW YORK.

ICE-CUTTER.

SPECIFICATION forming part of Letters Patent No. 728,555, dated May 19, 1903.

Application filed January 16, 1903. Serial No. 139,295. (No model.)

To all whom it may concern:

Be it known that I, JOHN DUCHARME, a subject of the King of Great Britain, and a resident of Roseton, in the county of Orange and State of New York, have invented a new and Improved Ice-Cutter, of which the following is a full, clear, and exact description.

My invention relates to machines for cutting ice upon the field; and the purpose of the invention is to provide a machine which is motor-propelled and in which the saw is driven from the motor.

Another purpose of the invention is to mount the forward portion of the machine upon runners and to provide such portion of the machine with bull or toothed supporting wheels for engagement with the ice in addition to the runners and means for quickly raising the forward portion of the frame, the rear portion trailing upon the ice, whereby the bull or toothed wheels may be carried upward from the ice to enable the machine to be readily turned around.

Another purpose of the invention is to provide simple and conveniently-operated means for elevating the saw, which saw is at the back portion of the machine.

The invention consists in the novel construction and combination of the several parts, as will be hereinafter fully set forth, and pointed out in the claims.

Figure 1 is a side elevation of the improved machine, and Fig. 2 is a plan view of the same.

A represents a platform of any form, preferably rectangular, and B represents an engine or a motor, which is duly mounted on the platform. A drive-shaft 10 is journaled in bearings 10^a, located at the front side portions of the platform in front of the engine or motor B, and this shaft 10 is provided with a crank-arm 11, and the piston-rod 12 of the engine or motor is connected with the said crank-arm 11.

The drive-shaft 10 is provided with a balance or fly wheel 13, as is shown in Fig. 2, the said wheel being usually near the left-hand end of the said shaft 10, and near the opposite end of the drive-shaft 10 a pulley 14 is secured. An axle 15 is mounted in suitable bearings secured to the under face of the

platform A at its front end, and traction-wheels 16 are secured to the said axle, the peripheral portions of which wheels are toothed, so that the said wheels may have purchase on the ice. Adjacent to the right-hand traction-wheel 16 a larger pulley 16^a is secured upon the axle 10, extending up through a suitable opening 17^a in the platform, and a driving-belt 17 is passed over the upper pulley 14 and around the lower and larger pulley 16^a, whereby when the drive-shaft 10 is operated the traction-wheels 16 will be rotated.

Near the right-hand end of the drive-shaft 10 a large pulley 18 is secured, and at the rear of the engine or motor B a transversely-located line-shaft 19 is mounted in bearings 20, secured to the platform A. On this line-shaft 19 a small pulley 21 is secured, together with a larger pulley 22, the latter being adjacent to the left-hand end of the said line-shaft. The pulley 21 is connected by a belt 23 with the pulley 18 on the drive-shaft 10.

A beam 24 at its forward end is pivoted in suitable standards 25, carried upward from the platform A, and at the rear or free end of the beam 24 a standard 26 is attached, preferably in the form of a yoke, and a pulley 27 is supported at the upper end of the said standard.

A rope, chain, or cable 28 is attached in any desired manner to the free end of the beam 24, and this rope, chain, or cable is passed over the pulley 27 and from thence downward to a drum 29, mounted to turn in suitable bearings at the rear end of the platform A. It will be understood that the said drum is provided with the usual ratchet-and-pawl device and is adapted to be turned by hand through the medium of a suitable crank-handle, as shown. The beam 24 when adjusted is prevented from leaving its adjusted position in any approved manner—as, for example, by passing a pin through apertures in the yoke 26 and in the said beam.

A bearing 30 is secured to the under face of the beam 24, midway of its ends, and in the said bearing a shaft 31 is mounted to turn, which shaft at its right-hand end has secured thereto a circular saw C, which is adapted to enter the ice over which the machine is

drawn and make a kerf in the same, while at the opposite end of the shaft 31 a pulley 33 is secured, and this pulley 33, which is smaller than the pulley 22 on the line 5 shaft 19, is connected with said pulley 22 by a suitable belt 34. The saw C extends above and below the platform A, a suitable slot 32 being made in the platform to permit of the upward and rearward passage of the saw.

10 It will be observed that by means of the windlass or drum 29 the beam 24 may be raised and lowered, so as to carry the saw C out of possible engagement with the surface over which the machine passes or permit the 15 saw to enter the said surface to the desired extent.

It will be observed that the rear portion of the platform is not wheel-supported and that it rests upon the ice; but at the forward end 20 of the platform A runners E are employed to support the platform in addition to the traction-wheels 16. These runners E have a sliding connection at their upper forward ends with the platform, which connection is made, 25 preferably, by attaching slotted plates 39^a to the platform and passing pins 39^b from the runners loosely through the slots in the said plates, so that preferably the forward ends of the runners E have a pivotal connection 30 with the forward end of the platform A.

When the machine is to be turned, it is necessary that the traction-wheels 16 should be raised out of engagement with the ice. To that end a toggle connection F is provided 35 between the rear ends of the runners E and the platform A, as is best shown in Fig. 1, and such toggle connection consists of two links, one pivoted to a runner and the other to the platform, and pivot-pins connecting 40 the said links. The toggle F at the right-hand side of the machine is provided with a connecting-rod 37, attached to its pivot-pin, and this connecting-rod is carried rearward and is pivotally connected with a crank- 45 arm 36, carried by a hand-lever 35, suitably mounted on the platform, and a transverse rod 38 is shown attached to the connecting-bar 37, which rod 38 is provided with a branch 38^a, extending forwardly and longitudinally 50 of the platform to an engagement with the pivot-pin of the left-hand toggle F, as is shown in dotted lines in Fig. 2, so that under this construction by moving the lever 35 in one direction the links of the toggles F are 55 straightened and the platform at its forward portion is raised, carrying the traction-wheels from engagement with the ice and leaving the runners E the sole supports for the forward end of the platform. Whenever it is 60 desired to propel the machine by the engine or motor B, the lever 35 is moved in a reverse direction and the links of the toggle F are carried rearward at right angles to each other, permitting the platform to drop sufficiently 65 to enable the teeth of the traction-wheels to engage with the ice.

The operator is stationed, preferably, on the

platform at any point to the rear of the engine or motor B.

At each side of the platform A a marker D 70 is pivoted. These markers are of the usual or of any approved type; but each marker has pivotally attached thereto a rod 39, and these rods extend in direction of each other over the platform A and are both pivoted to 75 the lower end of a lever 40, suitably mounted on the platform A, which lever is provided with the usual thumb-latch 41 to engage with a rack 42 of any approved type.

It will be observed that when the lever 41 80 is in a central position the markers will be out of engagement with the ice; but if the lever is drawn to the left, for example, the left-hand marker will be brought in engagement with the ice, while the right-hand marker 85 will be raised, and vice versa.

A clutch 43 is carried by the drive-shaft 10, and this clutch is adapted for engagement with the hub of the driving-pulley 18 and is operated through the movement of a lever 90 44, the handle of which may point either forward or rearward, as may be desired; but in the drawings the said shifting-lever 44 is shown pivoted upon a support attached to the engine or motor frame 45 and its handle 95 extends in direction of the front of the machine.

I desire it to be understood that the frame or bed of the machine can be curved more or less downward from the bearing of the saw 100 in a rearward direction to permit better adjustment of the saw and to provide a better bearing for the rear of the frame to trail upon the ice.

Having thus described my invention, I 105 claim as new and desire to secure by Letters Patent—

1. In an ice-cutter, a platform, a motor carried thereby, traction-wheels mounted underneath the forward portion of the platform to support said portion always above the ice, the rear portion of the platform being designed to trail upon the ice, a driving connection between said traction-wheels and said motor, a beam on the rear portion of said platform disposed longitudinal thereof, said beam being pivoted at its forward end to said platform, a saw carried by the central portion of said beam and adapted to extend downwardly through the platform, means for raising and lowering the free end of said beam and for supporting the same in its adjusted position to regulate the position of the saw, driving connections between the saw and the motor, runners pivoted at their forward ends to the 115 platform at a point in advance of the traction-wheels and extending rearwardly beyond said wheels, an operating-lever, and means for connecting said lever with the rear ends of the runners for raising and lowering the 120 same.

2. In an ice-cutter, a platform, traction-wheels mounted underneath the forward portion thereof to support said portion always

above the ice, the rear portion of the platform being designed to trail upon the ice, runners pivoted at their forward ends to the platform at a point in advance of the traction-wheels 5 and extending rearwardly beyond said wheels, links between the rear ends of said runners and the platform, said links being pivotally connected with each other at their inner ends, and at their outer ends pivotally connected to the runners and to the platform, connecting-rods pivotally connected to said links at their points of union with each other, and a lever for operating said connecting-rods to bring said links into line with each other to 10 spread the rear ends of the runners from the platform to elevate the forward portion thereof and cause the same to be supported on said runners, as set forth.

3. In an ice-cutter, the combination with a 15 platform, runners having sliding connection at their forward ends with the said platform, traction-wheels carried by the said platform at its forward end, a motor upon the said platform, a drive-shaft driven from the said motor, a driving connection between the said drive-shaft and the traction-wheels, links pivotally connected with each other and pivotally connected with the runners and the platform, connecting-rods pivotally connected 20 with the said links, a lever for operating the said connecting-rods, a line-shaft, a driving connection between the line-shaft and the drive-shaft, a saw extending through the platform, an adjustable support for the said saw, 25 a driving connection between the saw-spindle and the said line-shaft, markers pivotally connected with each side of the platform, rods pivotally connected with the markers and extending in direction of each other over the platform, a lever pivotally connected with the inner ends of said rods, and a locking device for said lever, as described.

30

saw-spindle and the said line-shaft, substantially as described.

4. In an ice-cutter, the combination with a platform, runners having sliding connection at their forward ends with the said platform, 40 traction-wheels carried by the said platform at its forward end, a motor upon the said platform, a drive-shaft driven from the said motor, a driving connection between the said drive-shaft and the traction-wheels, links pivotally connected with each other and pivotally connected with the runners and the platform, connecting-rods pivotally connected with the said links, a lever for operating the said connecting-rods, a line-shaft, a driving 45 connection between the line-shaft and the drive-shaft, a saw extending through the platform, an adjustable support for the said saw, a driving connection between the saw-spindle and the said line-shaft, markers pivotally connected with each side of the platform, rods pivotally connected with the markers and extending in direction of each other over the platform, a lever pivotally connected with the inner ends of said rods, and a locking device for said lever, as described.

In testimony whereof I have signed my name to this specification in the presence of two subscribing witnesses.
